UNITED STATES PATENT OFFICE.

FRANCIS A. NOLAN, OF ST. PAUL, MINNESOTA.

SHOE-SOLE.

1,297,720.

Specification of Letters Patent. Patented Mar. 18, 1919.

Application filed November 18, 1916. Serial No. 132,199.

To all whom it may concern:

Be it known that I, FRANCIS A. NOLAN, a citizen of the United States, residing at St. Paul, in the county of Ramsey and State 5 of Minnesota, have invented a new and useful Improvement in Shoe-Soles, of which the following is a specification.

This invention relates to certain new and useful improvements in rubber soles for 10 boots, shoes or other foot wear, and more particularly relates to a new article of manufacture which is especially designed for permanent attachment to such foot wear in a ready and efficient manner at the expenditure 15 of less manual effort and without sacrificing strength or rigidity at any point throughout its several dimensions.

This invention relates to a new article of manufacture consisting of rubber or other 20 resilient soles to be attached to boots and shoes or other foot wear as distinguished from rubber soles that are vulcanized to or integral with boots or shoes and attached thereto during the process of manufacture.

25 Heretofore soles of the type mentioned, namely rubber soles, have been reduced in thickness or made thinner throughout the entire shank thereof than the balance of the sole, that is the tread portion, in order to 30 enable it to be more easily attached and fitted to the arch; but this particular formation has been found objectionable due to lessened support at this point of the shoe and a consequent increased tendency to break 35 or crack.

An object of this invention is to so fashion the shank portion of the sole whereby full strength and rigidity are maintained and at the same time to permit the thorough and 40 easily accomplished fitting of the sole by the shoemaker to the shoe.

A further object is to mold the sole with an upper surface especially designed to aid by natural action the permanent attachment 45 of the sole to the shoe.

A still further object is to provide or form the ball portion of the sole with improved anti-skid means whereby tendency of the wearer of the thus equipped shoe to slip 50 in any direction is eliminated.

Other and further objects and advantages will be apparent from the following description.

In the drawing,

Figure 1 is a bottom plan view of the sole 55 equipped with the improved anti-slipping means;

Fig. 2 is a section taken on the line X—X of Fig. 1;

Fig. 3 is a section taken on the line Y—Y 60 of Fig. 1;

Fig. 4 is a section taken on the line W—W of Fig. 1;

Fig. 5 is a section taken on the line Z—Z 65 of Fig. 1;

Fig. 6 is a bottom plan view of a modified form of sole showing a slightly different pattern of anti-slipping means employed;

Fig. 7 is a longitudinal section taken on the line R—R of Fig. 6; and 70

Fig. 8 is a transverse section taken on the line S—S of Fig. 6.

Like numerals of reference refer to like parts in the several figures of the drawing.

In the drawing, the reference character 75 A, see Fig. 1, represents the fore part, B the shank, and C the heel seat of the sole which, as will be understood, is adapted for attachment in any desired manner, to either the shoe insole or to the upper thereof. In the 80 sectional views of this figure, the entire upper surface of the sole is illustrated as being suitably dished or otherwise provided with a continuous concave face 10, designed to contact evenly thereabout with the inner 85 sole or lower surface of the shoe, thus retaining the rubber sole in the desired and thoroughly effective position during the cementing action while the sole is being attached to the shoe as well as thereafter. 90

The preferred manner of constructing the sole is to provide the same with a flat or substantially flat base portion 12 of suitable thickness and of a shape generally conforming to that of the inner sole or shoe upper 95

to which it is to be attached but on a somewhat reduced scale; while extending completely around the edges of such base portion 12 is a flange 13 in the nature of a bevel of approximately equal thickness with that 100 of the base. When a rubber sole of the type described is attached to the shoe, a resulting natural suction and clinging tendency is effected which co-operates with the artificial

means employed to fasten the rubber sole in 105 proper position. Furthermore, the flange or bevel portion is of such nature as enables one to trim the same should there be a por-

tion thereof projecting beyond the shoe sole after the rubber sole has been secured in position.

It will be understood that the fore part 5 A of the sole is formed of a suitable thickness throughout and terminates at its rear extremity in the shank B, the central portion 14 of which is of equal thickness with the fore part A from whence it is chamfered off 10 along its longitudinal edges and at its rear extremity as shown at 15 and 16, respectively, to form side portions 17 and the heel seating portion C of less thickness than the tread and the central shank portion. In this 15 way, a rubber sole is provided, the shank of which is materially reinforced in strength and which still permits of the easy shaping thereof to the shoe.

In Figs. 6, 7 and 8, is shown a slightly 20 modified construction of sole with more especial reference to the shank thereof. As in the preferred form, the entire upper shoe contacting surface of the modification is concaved throughout; while at that portion 25 of the sole corresponding to or constituting the shank of the sole, the upper surface of the device is further cupped as shown at 18 to form a weakened portion extending centrally and longitudinally of the shank 30 throughout the length thereof, the portions 19 of the shank to either side of the cupped portion 18 being of equal thickness with the tread of the sole and terminating at their rear extremities in a heel seat or in a built 35 up integral heel 20 as shown in Fig. 7. When molding this form of sole, it will be understood the heel thereof may be equipped with suitable nail retaining devices such as the washers 21. By this construction, a de- 40 gree of rigidity and strength is afforded at the shank which is not present in rubber soles now on the market and at the same time the centrally weakened portion permits the flexing of the shank to render it easier of 45 attachment to the shoe.

In its completed form, the fore part of the sole is also provided on its exposed lower surface with a plurality of especially shaped and arranged corrugations 22 whereby tendency of the wearer to slip in any direction 50 is obviated. Figs. 1 and 6 show two patterns of the improved anti-skid means which

have been found to be most practical for the purposes. In both of these views, the corrugations, which are illustrated as being round- 55 ed on their outermost extremities, are spaced at parallel intervals and extend to each side of a common line, represented by the numeral 23, fashioned approximately longitudinally of the tread, the said corrugations 60 extending angularly rearwardly from said line, and the corresponding corrugations on opposite sides of the line diverging rearwardly therefrom. As shown, the corrugated patterns increase in transverse width 65 from their forward ends and are widest at or adjacent their rear ends where the greatest pressure is normally brought to bear. By this particular arrangement, it will be ap- 70 preciated that the possibility of slipping in any direction is minimized.

In accordance with the patent statutes, I have described the principles of operation of my invention, together with the sole which I now consider to represent the best 75 embodiment thereof, but I desire to have it understood that the construction shown is only illustrative, and that the invention can be carried out by other means and applied to uses other than those above set forth 80 within the scope of the following claims.

Having described my invention, what I claim as new and desire to protect by Letters Patent is:

1. A resilient shoe sole having a body 85 formed with a fore part and shank, the fore part and a portion of said shank extending from the fore-part to the heel line being of even thickness and the remaining portion of said shank being of less thickness, the 90 thick portion of said shank being beveled into said thinner portion.

2. A resilient sole to be attached to foot- 95 wear having a body formed with a flat upper surface and with a fore part, shank and heel, the heel and fore part being of different thickness and the shank having one portion corresponding in thickness with the fore part and the remaining portion of less thickness, said body having its marginal 100 portion extending upwardly.

In testimony whereof, I have signed my name to this specification.

FRANCIS A. NOLAN.
